J. F. STRAITZ

FLUID FUEL BURNER

Original Filed May 21, 1920

Inventor
John F. Straitz
Attorney.

UNITED STATES PATENT OFFICE.

JOHN F. STRAITZ, OF PHILADELPHIA, PENNSYLVANIA, ASSIGNOR TO NATIONAL AIROIL BURNER COMPANY, OF PHILADELPHIA, PENNSYLVANIA, A CORPORATION OF DELAWARE.

FLUID-FUEL BURNER.

Application filed May 21, 1920, Serial No. 383,187. Renewed September 13, 1923.

To all whom it may concern:

Be it known that I, JOHN F. STRAITZ, a citizen of the United States, residing at Philadelphia, in the county of Philadelphia, State of Pennsylvania, have invented a new and useful Fluid-Fuel Burner, of which the following is a specification.

My invention relates to improvements in fluid fuel burners. The object is to provide improved means for thoroughly breaking up the particles of fluid fuel and mixing the same with a fluid agent so that the mixture will be delivered to the combustion chamber in the form of vapor.

The device is especially applicable to the burning of crude oils.

The invention comprises means for compressing and then expanding the mixture to cause a thorough mingling of the fluid agent with the fluid fuel, to cause a churning of said mixture into a substantial emulsion.

The invention comprises means for adjusting the amount of fluid fuel that shall be drawn into the mixing chamber by the stream of fluid agent injected thereto so that a complete atomization of the fluid fuel is secured at a minimum expenditure of fluid agent, such as compressed air or steam.

The invention comprises means for pre-heating the burner before the introduction of fluid fuel thereto and for thoroughly cleaning the burner, after use.

The invention comprises other details of construction.

In the drawings, which illustrate merely by way of example, a suitable embodiment of my invention:—

Fig. 1 is a side elevation.

Fig. 2 is a longitudinal section.

Fig. 3 is a vertical cross-section on line 3—3 of Fig. 1.

Fig. 4 is an end elevation.

Fig. 5 is a horizontal section on line 5—5 of Fig. 2.

Similar numerals refer to similar parts throughout the several views.

The chambered body 5 is provided with the fluid fuel intake nozzle 6, and the fluid fuel chamber 7. At one end it is provided with the exteriorly threaded end 8 for receiving the cap member 9 provided with the interiorly threaded nozzle 10, and the passage or channel 11. Within the chambered body 5 is fitted the nozzle member 12

having a channel 13 registering with channel 11 of member 9. Threaded into the other end of member 5 is the nozzle member 14, having a rearwardly extending annular flange 15 surrounding but spaced away from the tapered discharge end of nozzle 12. The forward end of nozzle member 14 is provided with a suitable discharge vent 16 which, in the present example, is shown as a narrow horizontal slit.

Nozzle member 14 is also provided with a channel leading from the annular flanged portion 15 to the vent 16. This channel is shown as slightly flaring as at 17 at its flanged end, contracted at its intermediate part as at 18, and enlarged into a mixing chamber as at 19. In other words the channel leading from the discharge end of nozzle 12 to the vent 16 is in the form of a Venturi tube.

It will be noted that the threaded engagement of nozzle member 14 with the chambered body 5 is adjustable, so that the flanged portion 15 may be moved longitudinally with respect to the tapered nozzle of member 12 which serves to increase or diminish the annular space between flange 15 and said nozzle and thus serves to regulate the flow of fluid fuel from chamber 7 to channel 17.

It will also be noted that the cap member 9 serves to hold the nozzle member 12 in position in the chambered body 5.

In operation.

In operating for generating steam, steam is the most convenient and preferable fluid agent, while crude oil is the most available fluid fuel.

The steam is introduced at nozzle or port 10, passes through channels 11, 13, 17, 18 and 19 and passes out through vent 16. The preliminary passage of steam through the device is permitted until the temperature of the whole burner structure is brought to about 250° F. For this purpose the steam valve, not shown, which controls the passage of steam to nozzle or port 10 is only opened slightly to permit the steam to play through the burner to bring it up to the temperature mentioned.

The steam valve is then opened further to give the necessary pressure to operate the burner.

The oil cock, not shown which controls the flow to port or nozzle 6, is opened gradually until the proper proportion of oil and steam feed is secured.

5 The oil flowing into chamber 7, becomes highly heated and partially vaporized by contact with the hot walls of said chamber. It flows in a thin annular stream through the passage between the nozzle 12 and the flange 15.

10 This thin annular film of oil surrounds the stream of steam issuing from channel 13 of nozzle 12 into channel 17. The steam issuing from nozzle 12 into channel 17 tends to expand and work into the surrounding or enveloping film of oil, thus beginning the formation of a mixture of oil and steam. As the oil and steam enter the contracted throat 18, the mixture is compressed and the particles more intimately associated; as the

25 mixture emerges into the enlarged chamber 19 the particles expand and a further and more intimate admixture of the particles of oil and steam takes place. In fact the mixture is churned into an emulsion. The contracted vent retards the flow of the mixture from chamber 19.

30 This results in a further compression and then a discharge through the vent, in the form of a fan shaped vapor which upon ignition, burns with a clear flame, leaving practically no smoke or residue; all of the fuel is consumed without clogging the burner or forming any accumulation of carbon inside the combustion chamber.

35 The adjustment of the nozzle 14 with respect to chambered body 5, secures the de-

sired or required space between the margin of flange 15 and the tapered wall of nozzle 12. The space required depending upon the character of the fluid fuel or hydro-carbon used. The combustion chamber will attain a white heat and there will be no smoke.

40 When it is desired to shut off the burner, the oil valve is closed tight and the steam is permitted to play through the burner for 45 a short time, approximately a half a minute. This will clean the burner entirely free from oil, whereupon the steam cock is closed.

45 Where it is desired to use the burner in connection with the metallurgical art, it is 50 usually desirable to use compressed air as the fluid agent instead of steam. The principle of operation however is practically the same.

55 What I claim is:—

In an oil burner, the combination of a chambered body, having a burner nozzle and vent at one end thereof, a steam inlet port at the other end, and a fuel inlet port between the two ends, means forming a longitudinally extending channel from the burner vent, enlarged near the burner vent and contracted midway its extension, an annular flange formation at the inner end of the said channel projecting past the fuel inlet port, and a tapered nozzle connected with the steam inlet port and projecting a substantial distance within said annular flange formation and discharging toward the burner vent.

JOHN F. STRAITZ.

Certificate of Correction.

It is hereby certified that in Letters Patent No. 1,490,683, granted April 15, 1924, upon the application of John F. Straitz, of Philadelphia, Pennsylvania, errors appear requiring correction as follows: In the grant, heading to the printed specification and preamble, title of invention, for "Fluid-Fuel Burner" read *Fluid-Fuel Burner and Method of Burning Fluid Fuel*; page 1, lines 10, 17, and 22, before the word "means" insert the words *method and*; page 2, line 56, before the word "In" insert the numeral and period 1.; same page, after line 70 insert the following as claim 2:

2. The method of burning fluid fuel which consists in introducing the fuel into a region heated by a fluid agent and in a path of travel opposite to that of the fluid agent, then drawing the fuel from said region through a confined thin cylindrical path of substantial length by the inductive action of said fluid agent under pressure, so that the fuel will form a peripheral skin surrounding the fluid agent for a substantial part of their joint travel, then compressing the fluid agent and fuel toward their common axis, then expanding and again compressing the same to facilitate turbulence and thorough mixing, and then projecting the mixture in the form of vapor for combustion.

and that the said Letters Patent should be read with these corrections therein that the same may conform to the record of the case in the Patent Office.

Signed and sealed this 15th day of July, A. D. 1924.

[SEAL.]

THOMAS E. ROBERTSON,
Commissioner of Patents.
